UNITED STATES PATENT OFFICE.

HARRY A. LEWIS, OF NORRISTOWN, PENNSYLVANIA, ASSIGNOR OF ONE-HALF TO
ALAN D. WOOD, OF PHILADELPHIA, PENNSYLVANIA.

HEAT-TREATING APPARATUS.

Application filed October 16, 1924. Serial No. 743,986.

To all whom it may concern:

Be it known that I, HARRY A. LEWIS, a citizen of the United States, and a resident of Norristown, in the county of Montgomery and State of Pennsylvania, have invented a new and useful Improvement in Heat-Treating Apparatus; and I do hereby declare the following to be a full, clear, and exact description thereof.

10 My invention relates to heat treating apparatus and particularly to annealing furnaces and apparatus for handling the material to be annealed.

The invention constitutes an improvement 15 over my prior Patent 1,425,499, issued August 8, 1922.

One object of my invention is to provide an improved form and arrangement of furnaces of the character referred to.

20 Another object of my invention is to provide improved means of supporting and manipulating the material to be treated in the furnace.

One of the forms which my invention may 25 take is shown in the accompanying drawing wherein Fig. 1 is a view, partially in end elevation and partially in section, of a furnace arrangement and operating mechanism embodying my invention; Fig. 2 is a view, 30 partially in side elevation and partially in section, of the apparatus of Fig. 1; and Fig. 3 is a sectional plan view of the apparatus of Figs. 1 and 2.

The furnace comprises a lower compartment 35 hereinafter termed the water chamber, having a bottom wall 5, end walls 6 and side walls 7 that may be formed of reinforced concrete or other suitable material. Supported upon the side and end walls of 40 the chamber 4 is an annealing chamber 8 through which the articles to be heated are passed. The chamber is provided with the usual top and side walls and the end doors 9 and 10. The chamber 8 is supported intermediate its ends by longitudinally and 45 transversely extending I-beams 11 and 12, (Fig. 2) whose ends are embedded in or supported by the walls 6 and 7 of the lower chamber 4.

50 The bottom of the chamber 8 is preferably composed (Fig. 3) of sheet iron 13, red brick 14 and fire brick 15, though of course other material may be employed if desired.

The bottom of the annealing chamber 8 55 is provided with elongated openings 16 that

are disposed in staggered relation as shown in Fig. 3, for a purpose hereinafter to be described. The furnace is likewise provided with flues 17 that lead to the stack 18, and the stack 18 is provided with a damper 19. 60 The chamber 8 may be heated either electrically or by combustion.

The water for the chamber 4 is supplied from any desired source, and the level therein is preferably maintained at the level of 65 the overflow pipe 20 (Fig. 1). A drain valve 20^a is also provided to clear the chamber of water when desired. The overflow and the water is drained off to a cooling reservoir through a pipe 21. Water may of 70 course be supplied to the chamber 4 continuously or intermittently, as desired.

Pairs of pillars or piers 22 are mounted within the chamber 4 for supporting shafts 23 upon which are mounted rocker arms 24, 75 pivotally connected to and spaced axially of the shafts 23. To the outer end of each arm 24 is connected a lever or oscillator 25. The oscillators 25 are provided intermediate their ends with enlargements 26 that are ringlike 80 or annular in form, for the reception of eccentrics 27. The eccentrics 27 are rigidly secured to shafts 28 that are rotatably supported in bearings 29 (Fig. 1) and are provided on their outer ends with beveled gear 85 wheels 30, some of the gear wheels being omitted in Fig. 2 for the sake of clarity.

The gear wheels 30 are driven by bevel pinions 31 that are mounted upon a shaft 32 which is connected through a beveled gear 90 wheel 33 with a bevel pinion 34 mounted upon a shaft 35 which is driven by differential mechanism 36 having worm wheels 37 that are driven by motors 38. This arrangement of motors and differential mechanism 95 makes for uniformity of speed and smoothness of movement of the apparatus just described.

To operate the apparatus, the doors 9 and 10 are first opened by means of a motor 40 which, through suitable connections, moves the chains 41 that are connected to cords or cables 42, that pass around suitable sheaves, as shown in Fig. 2, and are connected to the doors 9 and 10 to raise 105 the same. The motors 38 are then started to operate the eccentrics 27 and impart an oscillatory movement to the levers 25. Sheets of material 43 are supplied through the furnace door 9 and are engaged by the 110

upper ends of the levers 25. Preferably the levers 25 are actuated at a relatively fast speed during this stage of the operation. As soon as the material has entered the furnace the doors are closed and the speed of the motors 38 reduced so that the material will move through the furnace at a low rate of speed in order that it may be properly heat-treated by the time it reaches the outlet door 10. The purpose in continuously moving the sheets of material 43 while in the furnace is to avoid streaking or marking of the sheets by reason of their contact with the levers 25, and to maintain the heated air in the furnace in a state of agitation so that sheets will be uniformly heated.

The purpose of the water chamber is to lubricate the bearings of shafts 32, 23 and 28 that are located within the chamber as well as the bearings for the other moving parts contained therein, and also to prevent such mechanism from becoming overheated through heat being conducted thereto through the annealing chamber. Further they protect the bearings from dust which may fall through the openings 16, in that such dust will not circulate through the chamber 4.

30 The shafting within the chamber 4 may preferably run in rubber bearings without oil. A stuffing box 45 is provided in the end of the chamber 44 to prevent leakage of water along the shaft 32.

35 Claims to the mechanism for moving the material form the basis of my application, Serial No. 744,199 filed October 17th, 1924.

Various changes in detail and general arrangement may be made without departing from the spirit and scope of the invention as defined in the accompanying claims.

I claim as my invention:

1. Heat treating apparatus comprising an annealing chamber, a cooling chamber disposed therebeneath, oscillatory members

50 mounted within said cooling chamber and having projecting portions extending into said annealing chamber for moving the material to be annealed, and means for supplying cooling fluid to said cooling chamber.

2. Heat treating apparatus comprising an annealing chamber, oscillatory members mounted exteriorly of said chamber and having projections extending into the chamber, for moving the material to be treated, 55 and means for supplying cooling liquid to the bearings of said members.

3. Heat treating apparatus comprising an annealing chamber, a chamber therebeneath for containing cooling liquid, actuating members mounted within said cooling chamber and extending into the annealing chamber for moving material to be treated, driving mechanism mounted exteriorly of the cooling chamber and having driving connection with said actuating members. 65

4. Heat treating apparatus comprising an annealing chamber, a chamber therebeneath for containing cooling liquid, actuating members mounted within said cooling chamber and extending into the annealing chamber for moving material to be treated, driving mechanism mounted exteriorly of the cooling chamber and having driving connection with said actuating members, the 70 bearings for actuating members being disposed beneath the surface of the liquid of the cooling chamber, and the driving connection from said driving mechanism extending through one wall of the cooling 75 chamber.

5. Heat treating apparatus comprising a heated chamber, cooling apparatus disposed adjacent to said chamber, and means cooled by means of said apparatus for moving material in said chamber. 85

In testimony whereof I the said HARRY A. LEWIS have hereunto set my hand.

HARRY A. LEWIS.
